UNITED STATES PATENT OFFICE

WALTER E. KING AND JAMES S. ABERCROMBIE, OF HOUSTON, TEXAS; SAID KING AS-
SIGNOR TO SAID ABERCROMBIE

BLOW-OUT PREVENTER

Application filed January 15, 1929. Serial No. 332,653.

Our invention relates to an automatic operating apparatus for closing a passage at a time when there is a high pressure of fluid therein.

5 Our device is particularly adapted for use in combination with a blowout preventer such as is used on the casing head of deep wells, where enormous gas pressures are encountered.

10 It is one of the objects of our invention to provide a device which will operate automatically when the pressure in the passage increases.

It is another object of our invention to 15 construct a device which may be operated by fluid pressure from an external source and at the same time may be operated by the pressure encountered in the passage.

Still another object of our invention is to 20 provide a ram for closing the passage, which ram has connected thereto a piston, which has a greater exposed area than the area of the ram.

A further object of our invention is to 25 construct a device which will close without the use of external fluid pressure but will operate merely by the pressure encountered in the passage.

Other and further objects of our invention 30 will be readily apparent to those skilled in the art to which our improvement appertains when the following description is considered in connection with the accompanying drawings wherein—

35 Fig. 1 is a central vertical section through a blowout preventer equipped with our improvements and showing the rams in open position.

Fig. 2 is a view similar to Fig. 1 but showing the rams in closed position.

The present invention is shown as applied to a type of blowout preventer somewhat similar to that disclosed in the prior application for patent of James S. Abercrombie, 45 Serial No. 278,415, filed May 7, 1928, and is also somewhat similar to the subject matter disclosed in our co-pending application No. 332,280, filed January 14, 1929.

The blowout preventer is a device adapted 50 for attachment to the upper end of the well

casing and serves as a means of closing the passage about the drill stem to prevent a flow of gas or fluid therefrom. It often occurs that when a gas pocket or formation is encountered, pressures as high as 2500 pounds per square inch force the material in the well up through the casing. It is essential that when the gas is encountered that the well passages be instantly closed before the gas and other materials can get under headway. 55 If the gas once starts to flow or, what is known as blow, then it is very difficult to close the passage as sand and gravel will travel at enormous rates of speed and under very high pressure. This is one of the greatest sources of danger in bringing in a well as if a pebble or piece of gravel strikes the iron casing a spark may result which ignites the well and causes a tremendous loss in production and well equipment. 60 65 70

We have shown in the drawings a device constructed in such a manner that it will be operable by an increase in pressure occurring in the well passage. By having reference to the drawings, a flange or coupling member 1 is shown as internally threaded at 2 for attachment to the casing, casing head or an extension thereof. This flange 1 is adapted to be secured to the lower flange 3 of the blowout preventer body 4; any suitable means of attachment, such as bolts 5, may be used to secure these two members together. 75 80

The body 4 has a central passage 6 therethrough to accommodate the drill stem 7 or other tools which are being used in drilling a well. The body 4 is formed with a pair of diametrically disposed cylinder openings 8, which are adapted to permit reciprocation of a pair of rams 7. The particular formation and construction of these rams forms no part of the present application as they are covered in the previous application of J. S. Abercrombie. These rams are connected to pistons 17 by suitable piston rods 10 which pass through a pair of stuffing boxes 11 and 12, carried by a coupling member 15. This member 15 may be formed in one or more portions and has attached thereto a cylinder 16, which is adapted to receive the piston 17. 85 90 95 100

which is connected to the piston rod 10 and causes movement of the ram 7.

We have shown inlets 19 and 19' to the cylinder 16 which permit external fluid pressure, such as steam, air, or gas from an outside source to be passed into the chamber to operate the piston 17 and open or close the ram 7, as desired.

When the well starts to blow the pressure which may be passed into the cylinder 16 from the inlets 19' has been found to be insufficient to move the ram 7, as in the event steam pressure is used the pressure in the boilers is usually around three or four hundred pounds at most, so that if gas at a thousand pounds is encountered it is absolutely impossible to close the rams 7. Various types of devices to assist in closing the rams 7 under these enormous pressures have been devised, such as a screw spindle which penetrates through the end of the cylinder 16 and carries a wheel or is adapted to receive a wrench for turning it, so that the piston may be forced inwardly. However, this type has been found to be unsatisfactory as sufficient leverage can not be obtained in order to close the ram before it is seriously injured and worn away by the terrific force and the passage of mud and gravel. It must be remembered that when the well starts to blow after the rams 7 are only partially closed that the abrasion of sand and gravel takes but a few moments to wear away the face of the ram so that if they are subsequently closed they do not form a complete closure about the drill stem and are unsatisfactory for the purpose for which they have been designed.

In view of the foregoing it is absolutely necessary that the rams be closed instantly and that a pressure greater than the pressure in the well bore be instantly available to move them to closed position. With this in view, we have devised a structure in which a bypass 20 has been made from the passage 6 to a point 21 in the head of the cylinder 16. A suitable valve 22 is shown in this bypass which may be manually or otherwise operated. It should be noted at this time that the face 18 of the piston 17 has a greater exposed area to be acted upon by the fluid pressure than has the ram 7. This is one of the features of our improvement as when taken in connection with the bypass 20 it is apparent that any pressure occurring in the passage 6 will be instantly transmitted to the face 18 of the piston 17. Inasmuch as the area 18 is greater than the area of the ram 7, exposed to the same pressure, it is obvious that a greater force will be exerted on the face 18 and the friction of the parts is all that is necessary to be overcome in order that the ram 7 will move to the closed position, as is shown in Fig. 2.

When a well starts to blow a very dangerous situation arises and the drillers and other

employees about the well are in fear of the well catching fire, so that it is usual procedure for them to immediately leave without taking the precaution to close a manually operable blowout preventer or other device to save the well. With our improved blowout preventer any increase in pressure in the well bore is immediately transmitted to the piston 17 and the rams 7 are moved to closed position without any effort on the part of the employees, so that even though they leave, the blowout will be prevented.

We have shown an inlet 25 to the cylinder 8 which may be closed by a suitable plug. This inlet is formed in order that the present device may be used in connection with the arrangement as disclosed in our co-pending application, Serial 332,280 filed January 14, 1929, but does not form any of the subject matter of the present application. The valve 22 is preferably of a type which will open only when subjected to a pressure exceeding a predetermined amount, even though the handle is set for open position. Such a valve is disclosed in the application of Walter E. King, Serial No. 332,657 filed January 15, 1930.

While we have shown and described herein an embodiment of the present improvement which we believe to be entirely satisfactory and practical for the purpose in view, nevertheless it is to be understood that the several essential parts of the device may be constructed in various other alternative forms and it is accordingly to be understood that in the further development of the device we reserve the privilege of resorting to all such legitimate changes therein as may be fairly embodied within the spirit and scope of the invention as claimed.

Having described our invention, what we claim is new and desire to protect by Letters Patent is:

1. In a blowout preventer, rams to close the well bore passage, pistons connected to and operable in a separate chamber from said rams, fluid pressure means to move said pistons, and a bypass from the well bore to a point behind said pistons.

2. In a blowout preventer, rams to close the well bore passage, pistons connected to and operable in a separate chamber from said rams, fluid pressure means to move said pistons, and a bypass from the well bore to a point behind said pistons, whereby the pressure in the well bore on said rams is equalized by the same unit area pressure on said pistons.

3. In a blowout preventer, rams to close the well bore passage, pistons connected to and operable in a separate chamber from said rams, fluid pressure means to move said pistons, and a bypass from the well bore to a point behind said pistons whereby the pressure in the well bore on said rams is equalized

by the same unit area pressure on said piston,
said pistons having a greater exposed area
than said rams.

In testimony whereof we have hereunto affixed
our signatures, this the 10 day of January,
A. D. 1929.

JAMES S. ABERCROMBIE.
WALTER E. KING.
